THREAD-CUTTING MECHANISM FOR SEWING MACHINES.

1,016,027.

Specification of Letters Patent.

Patented Jan. 30, 1912.

Application filed February 19, 1904. Serial No. 194,383.

To all whom it may concern:

Be it known that I, DANIEL MILLS, a citizen of the United States, and resident of Philadelphia, in the county of Philadelphia and State of Pennsylvania, have invented certain new and useful Improvements in Thread-Cutting Mechanism for Sewing-Machines, of which the following is a specification.

10 This invention relates to improvements in sewing machines, and especially to that class of sewing machines in which the mechanism is automatically stopped after making a desired predetermined number of stitches, as for example, in button-sewing, buttonhole stitching and bar-tacking machines, in all of which the desired number of stitches are sewed at one point in the work, as at a button or buttonhole, and the machine then 20 stopped and the work shifted before re-starting the machine. In machines operating in this manner, as for example, in a button-sewing machine, which is the type of machine shown in the drawings of this application to illustrate my invention, a button is sewed to the fabric, the machine stopped, and the work then drawn through the machine to locate the fabric at another point at which another button may be sewed to the 30 same. In such machines as heretofore constructed the needle and the bobbin threads are usually both pulled or drawn along with the fabric as the latter is shifted, and there is consequently much waste of thread there- 35 by caused, as the thread is continuous, spanning the space from button to button, and is usually cut by the operator after the sewing en. of the button is completed. This cutting operation of course causes a considerable 40 less of time in addition to the waste of thread.

In a prior application filed by me May 23, 1902, Serial No. 108,667, I have illustrated a mechanism which avoids the waste 45 of thread and loss of time incident to the type of sewing machine just described, the mechanism shown in my prior application being operative for cutting the needle and bobbin threads after the sewing mechanism 50 has made the desired number of stitches at a given point and has been automatically stopped, the cutting of the threads being

performed in such mechanism by a suitable thread-cutter brought into action before the work is shifted into a new position, and 55 preferably at about the time that the presser-bar is raised to release the work. In the mechanism shown in said prior application means were provided for pulling out a sufficient length or quantity of thread from 60 both the needle and bobbin thread supplies to allow for the proper formation of the first stitch on the re-starting of the machine. In such mechanism the needle-thread loop cast off by the looper during the formation of the last stitch of a predetermined number or series was received and detained in such a manner as to cause an additional length to be drawn from the needle-thread supply by the usual take-up device, and an 65 additional length was drawn from the bobbin-thread supply by a suitable pull-off, the latter device having been operated by manual means subsequent to the automatic stopping of the machine, and the means for 75 causing an additional length of thread to be drawn from the needle-thread supply having been automatically brought into action just prior to the stopping of the machine and during the formation of the last stitch 80 of a series.

In the present invention I retain the essential features of the means shown in said prior application for drawing off an additional quantity of thread from the needle-thread supply on the formation of the last stitch of a series, but I provide in lieu of the bobbin-thread pull-off device novel means for clamping the bobbin-thread and holding it so clamped until a predetermined point is 90 reached in the operation of the machine after the same has been restarted.

One of the principal features of my present invention is the provision in connection with a thread-clamp, and particularly a 95 thread-clamp for engaging and holding the bobbin-thread, of manual and automatic means for operating said thread-clamp, the manual operating means serving to clamp the thread after a predetermined number of 100 stitches has been made and the machine stopped, and the automatic means serving to release such clamp after the machine has been re-started and a sufficient number of

stitches locked in place in the work to prevent the pulling out of the thread. The means preferably employed for the purpose of holding such bobbin-thread in place until 5 a sufficient number of stitches has been made is a combined thread cutting and clamping device, the working stroke of which is controlled manually and the return stroke of which is effected automatically at the proper 10 time. This combined cutting and clamping device operates to sever the bobbin-thread and at the same time clamp it firmly in place.

Another important feature of the present 15 invention is the provision in connection with such a device as that just described, to wit, a thread clamp or combined thread cutting and clamping device, of means for exerting such a clamping pressure thereon 20 as will prevent movement thereof during the interval between the manual operation of the device to the clamping position and the automatic return of the same to the inoperative position, and also assure its positive 25 clamping action when in clamping position. This result may be accomplished in any desired manner, but I prefer to utilize the downward pressure exerted by the presser-bar. An important feature of this 30 construction is the mounting of the thread-clamp upon the throat-plate and the exertion of the clamping pressure downward upon said thread-clamp, preferably by means of a clamping-plate operated by the 35 presser-bar and which has a slight movement sufficient to force the thread-clamp into frictional clamping engagement with the upper surface of the throat-plate upon which it is supported.

40 Other features of the invention not hereinbefore referred to will be hereinafter described and pointed out in the claims and are illustrated in the accompanying drawings, in which—

45 Figure 1 is a front elevation of a Standard button-sewing machine embodying my present invention. Fig. 2 is a rear view of the same. Fig. 3 is a substantially central horizontal section of the same, the section being taken in the line 3—3, Fig. 1, looking from above. Fig. 4 is an underside view of the same, partly in section, the section being taken in the line 4—4, Fig. 1. Figs. 5, 6, 50 7 and 8 are details of the thread cutting and clamping device, with associated elements for operating the bobbin-thread cutting and clamping device manually and automatically at different times, and illustrate the principal operative positions of such parts at various 55 stages of the operation of the machine. Fig. 9 is a sectional front end elevation of a detail illustrating a pull-off device controlled by the stop mechanism, as will be hereinafter described. Figs. 10 and 11 are 60 65 enlarged sectional details taken respectively

on line 10—10 of Fig. 8 and line 11—11 of Fig. 7, and illustrate the manner in which the bobbin-thread cutting and clamping device operates to cut the bobbin-thread and then clamp the severed end in place. Figs. 70 12 and 13 are enlarged sectional elevations of the stitch-forming mechanism and of the loop-detainer and spreader co-operative therewith, taken on lines 12—12 and 13—13 of Fig. 2, showing the respective positions 75 of said detainer and spreader when it is out of action and when in its operative position. Figs. 14 and 15 are top and side views respectively of the loop-detainer and spreader removed from connection with the machine. 80

Similar characters designate like parts in all the figures of the drawings.

In said drawings, I have illustrated one type of sewing machine, in which the stitch-forming mechanism is adapted to be automatically stopped after making a predetermined number of stitches, the machine shown being a button-sewing machine of the well-known "Standard" sewing machine type, although my invention is equally applicable 90 to other sewing machines for other purposes than for sewing on buttons. Many of the parts illustrated are of well-known construction and are for convenience of illustration substantially as found in said "Standard" 95 sewing machine, some of said parts being a bed-plate 1, an overhanging arm 2, an upper driving shaft 3 supported in bearings in said arm 2, a vertically-reciprocating needle-bar 4 operated from the driving shaft 3, a 100 rotary shuttle or looper 5, a shuttle-driving shaft 6 supported in suitable bearings on the under side of the bed-plate and operated from the upper shaft 3 by suitable connections, a take-up device 7, operated in the 105 usual manner from the upper shaft 3, a presser-bar 8 operating in the usual manner, a button-holder carried by said presser-bar, and suitable mechanism for shifting said button-holder for presenting the holes in the 110 button to the needle in the proper manner, together with automatic stop mechanism for stopping the stitch-forming mechanism and other working parts at the end of a determined number of stitches, various minor devices being also shown, to which special reference need not be made.

The button-holder carried by the presser-bar may be of any suitable construction, and is preferably detachably clamped to the 115 presser-bar between a pair of nuts 10—10, said button-holder having the usual button-gripping jaws 13—13, between which a button may be firmly held.

The button-holder may be vibrated back 120 and forth to present first one and then another of a pair of holes in the button in a position to be entered by the needle in the following manner: The presser-bar, to which the button-holder is secured, is vi- 125 130

brated back and forth in a direction transverse to the bed-plate by the usual operating connections employed in this machine, and as said presser-bar is vibrated, the button-holder, and the button carried thereby, are also moved back and forth to present a pair of holes in the button to the needle alternately. The button-holder is also pivoted to swing relatively to the presser-bar about the pivot 12 for the purpose of presenting the second pair of holes in the button in position to be entered by the needle. This swinging movement may be communicated to the button-holder by a connecting-rod 28 adjustably secured to the rocker-arm or lever-arm 27 attached to the upper end of a short vertical shaft 25 extending through the bed-plate and working in bearings at opposite sides thereof, and is derived from a rotary switch-cam 24 through another arm 29, which latter is secured to the lower end of the shaft 25 and provided with a pin which works in the groove of said cam and causes the shifting of the connecting-rod 28 and the button-holder at the proper time. This cam is geared directly to the shaft 6 and driven therefrom by worm gearing.

Any suitable automatic stop mechanism may be employed for stopping the machine after making a predetermined number of stitches, a desirable form being that shown and described in my prior Patent No. 635,267, dated October 17, 1899. In the present case, as in said patent, the shaft 3 has the usual hand-wheel or pulley 34 fast thereon and a driving or loose pulley 35 adapted to be clutched to, and unclutched from, said fast pulley 34. For the purpose of coupling these pulleys an elbow-lever 36 is pivoted on a bracket-arm 37, and one end of this elbow-lever extends into an opening in a vertically operating slide-bar 39 and is adapted to be actuated thereby. The other or outer end of said elbow-lever extends into position to actuate a sliding-pin 40 controlling the clutch movement of the pulley 35. At its lower end the slide-bar 39 is connected by a link 42 to a lever 43, one end of which latter is pivoted on a lug 44, while the opposite end of said lever is bifurcated and embraces a pin projecting from a rock-arm 45 carried by a rock-shaft 46 suitably supported below the bed-plate. This shaft 46 is rocked in the proper direction whenever it is desired to couple the pulleys 34 and 35, and when the pulleys are clutched together the elbow-lever 36 and the slide-bar 39 are held in position to effect such clutching by a suitable latch, such as the horizontally acting spring-pressed slide-latch 49, engaging with the said slide-bar. By withdrawing the slide-latch 49 from engagement with the slide-bar 39 the latter will be automatically elevated and the

other parts returned to a position to release the loose pulley 35 from the fast pulley 34, a spring 54 being employed to effect this return movement.

The fast pulley has two stop-rings 57 and 58 yieldingly connected therewith, in a manner as fully disclosed in my said prior patent. These stop-rings are each provided with a projecting lip or stop-face, one of which, that on the ring 58, being adapted to strike the upper end of the slide-bar 39 when the latter is released by the slide-latch and forced upward by the spring 54, so as to stop rotation of the pulley in one direction, while the ring 57 may have a slight over rotation due to the momentum of the connected operating parts, in which event it may be returned to the normal stopping point by means (not shown) similar to that shown in my prior patent.

The stop mechanism is intended to be controlled automatically, and I have shown herein a releasing-bar 70 pivoted to the lever-arm 27 and having a hooked rear end for engaging and releasing an elbow-lever 74 and also having a cam face 70" coöperative with a fixed pin 70''' for shifting the position of the hooked end of the bar. The hooked end of the bar 70 does not operate the lever 74 to automatically stop the machine until the bar 70 is pulled toward the needle during the formation of the last of the determined number of stitches, when said arm 70 is shifted by the lever-arm 27 and the slide-latch 49 is released from the slide-bar 39, whereupon the sewing operation is automatically stopped by the parts previously described.

In the present machine, as in that shown in my prior application, the automatic stop mechanism is intended to control the throwing into action of a device for engaging and detaining the last needle-thread loop cast off by the shuttle after a series of stitches, and for spreading said loop to permit the cutting of one side thereof without cutting the other. This loop-detainer or loop detainer and spreader is normally held out of action and is brought into operation just prior to the casting off of the last loop by the shuttle prior to the automatic stopping of the machine. This loop-detainer is designated by 75 and is a swinging arm secured to the forward end of a short rock-shaft 70' journaled in bearings below the main shaft 6 and having at its rear end another rock-arm 71 carrying an antifriction roller 72 which normally rides on the under side of the cam-wheel 24. This cam-wheel has a cam-face or locking recess 24' which controls the throwing of the loop-detainer into operation, this being accomplished by the antifriction roll 72 snapping into said recess when the cam-wheel brings the recess around opposite the roll. A spring, such as 73, 120

serves to force the roll into such recess, which then locks the roll in place, and the rock-shaft 70' and the loop-detainer 75 are by this movement oscillated and the latter brought to its working position. The operations of the parts are so timed that the loop-detainer is not thrown into action until the last loop of the series of stitches is cast off by the shuttle. The loop detainer and spreader has a hook 76 forming a recess 77 in which the needle-thread loop is received, and said detainer may also have a spreader, such as the lateral wing or flange 78, for spreading the two sides of the loop to enable the cutter hereafter described to cut one side only of the loop-thread or needle-thread without severing the other. The hooked portion of this spreader forms a guide for the loop, as shown in Fig. 13, and may be stopped in its working position when thrown into action by the spring 73, by a wall 80 of the shuttle-race or any other suitable stop-face. When the detainer is stopped, as shown, the loop cast off by the shuttle enters the recess 77 without meeting any obstruction and is detained by the end wall of said recess and spread by the lateral wing 78. Owing to the fact that this last loop of a series is detained and not drawn up into the work by the take-up, it is necessary to provide means for relieving the tension on the needle-thread at such time and while the take-up is completing its take-up movement so that the additional length of thread made necessary by reason of the loop passing around the detainer may be drawn from the spool by the take-up without liability of breakage. Any ordinary type of tension device, such as indicated at 85, may be employed for tensioning the thread, but instead of the tension-releasing device shown in my prior application, I make use of a pull-off device which is arranged to engage with the thread at a point between the spool and the tension and which is operative upon the starting of the machine to pull off a certain amount of thread from the spool, and subsequently, preferably during the formation of the last stitch of a series, to give up such thread so as to slack the same between the spool and the tension device and thereby relieve it of all drag or tension other than that provided by the tension device itself. This I have found in practice sufficiently relieves the thread of tension to permit it to be drawn from the spool during the formation of the last stitch without liability of breakage.

The pull-off, as herein shown, comprises a lever 87 which is pivoted upon the machine at a suitable point, such as 87', adjacent to the spool or needle-thread supply, and is operatively connected with the slide-bar 39 of the automatic stop-mechanism so as to be controlled thereby by means

of a pin-and-slot connection 88 (see Fig. 9). At its free end this lever 87 may have an eye or opening 87" through which the needle-thread may pass. In this construction the pull-off lever 87 is movable in a direction crosswise of the head 2 and is normally stationary during the operation of the machine in the position shown in dotted lines in Fig. 9, to which position it is moved to pull off thread from the spool when the slide-bar 39 is lowered upon the starting of the machine, but is automatically thrown to the position shown by full lines in said figure when the slide-bar 39 rises on the automatic stopping of the machine, in which position it slacks the thread for the purpose before described.

In all of the principal views the mechanism is shown with the parts in the positions occupied immediately after the machine has been brought to a stop by the action of the automatic stopping mechanism. All of the parts are now in position to permit the cutting of the needle and bobbin threads and the release of the work from the button-holder. In the foregoing description I have set forth the manner in which the needle-thread is held and a considerable length of thread provided to form a cut end, it being necessary that the length of the severed end of the needle-thread below the eye of the needle shall be sufficient to permit the formation of the stitch when the machine is started again automatically. In the construction shown in my prior application a considerable length of thread at the cut end of the bobbin-thread is provided for the same purpose. In the present case, however, I cut the bobbin-thread without providing any extra length of thread, and the end so cut is immediately clamped until the machine is restarted and a sufficient number of stitches properly formed to lock the bobbin-thread firmly in the work. The means for cutting and clamping the bobbin-thread is associated with the loop-detainer and spreader and preferably co-operates directly with a needle-thread cutter, separate means being employed for severing the needle-thread and the bobbin-thread, instead of a single cutter being employed to cut both threads, as in my prior application.

The principal feature which distinguishes my present invention from that shown in my prior application is the bobbin-thread cutting and clamping means, and the manner in which this is constructed and operated will now be described. In the preferred construction the bobbin-thread cutting and clamping means will be actuated by the same manual actuating mechanism as the means for cutting the needle-thread, and the manual action will be similar to that for controlling the cutting of the threads in my prior application. The bob-

bin-thread cutting and clamping functions are preferably combined in a single movable element mounted directly upon the throat-plate 100 and preferably pivoted thereto in such a manner that the combined bobbin-thread cutting and clamping device, which is designated generally by 101 and is pivoted at 101', will move across said throat-plate and the needle opening therein. The device as shown is substantially in the form of an angle-lever with a hooked end having an opening between such hook and the body of the device in order to form a space through which the needle may pass. The upper outer edge of the hooked part of the device is in this case the cutting edge and the lower outer edge of said hook is the clamping edge and is preferably rounded. These cutting and clamping edges are clearly illustrated at 101'' and 101''' in Figs. 10 and 11, from which it will be seen that the movable cutting or shearing edge of the device coöperates with one fixed face or member to shear the bobbin-thread 102, and that the other rounded clamping edge coöperates with another fixed face or member to bind or clamp between such parts the severed end of the thread. The fixed member which coöperates with the clamping edge of the bobbin-thread cutting and clamping device is the upper side of the throat-plate 100 at the edge of the needle opening therein, and the member which co-operates with the cutting edge of said combined cutting and clamping device is preferably a substantially fixed clamping plate 99 having a needle opening 99' therein, one edge of which constitutes a cutting edge which coacts with the cutting edge 101''. This clamping plate constitutes an element for exerting a clamping pressure on the bobbin-thread cutting and clamping device 101, and the clamping plate preferably has a slight vertical movement for the purpose of clamping the device 101 which lies under it and upon the throat-plate 100 and taking up wear of the parts and compensating for slight differences in the thickness of the thread. This slight movement of the clamping-plate may be obtained by securing the plate at one edge only, as for example, at the points 98, it being in this case mounted in a cutaway portion of the throat-plate and held thereto by screws at the points 98 so as to leave the part of the clamping-plate adjacent to the needle-opening relatively free. The clamping pressure is best exerted in a downward direction upon the plate 99 and preferably is controlled by the presser-bar, the part which acts directly upon the clamping-plate in this construction being the button-holder secured to the foot of the presser-bar. This mechanism constitutes a means for normally clamping the bobbin-thread cutting and clamping device between

the clamping plate and the upper side of the throat-plate.

Any suitable form of needle-thread cutter may coöperate with the parts just described and with the loop-spreader to sever the needle-thread at one side of the loop formed by such spreader. In my prior application I have illustrated a movable and a fixed shear for accomplishing this result, but in the present case I have shown a pair of movable shears, one of which is indicated at 103 and is a short lever pivoted at 105' below and at one side of the needle opening in the throat-plate and pivoted in turn to a coacting movable shear 106 near the center of a long arm which carries said shear and in turn is pivoted at 106' at a point remote from the needle opening in the throat-plate (see Fig. 4). These two coacting shears constituting the needle-thread cutter are oscillated in opposite directions by means of a long connecting-rod, such as 113. It should be understood that these two movable shears operate in contact with each other and in the path of one side only of the loop carried by the spreader, and that the other side of the loop is not cut by such shears. Hence a long end depends through the opening in the throat-plate on the drawing up of the needle, this end being of sufficient length to permit the proper formation of the first stitch upon the re-starting of the machine.

The parts just described for cutting the threads may be operated in any suitable way, but I prefer to organize them in such a manner that they will coöperate with the presser-bar and presser-foot, which latter in this case is a part of the button-holder, this mode of organizing the parts being desirable in order that the operator may cut the threads and raise the button-holder from the work into a position where the button may be disengaged from the holder and the work shifted, by a single operation. Moreover, I prefer to provide manually controlled means for actuating the needle-thread cutter and the bobbin-thread cutter and for returning the needle-thread cutter, and to make use of automatic means for returning the bobbin-thread cutting and clamping device. The connecting-rod 113 just referred to constitutes a convenient means for operating both the needle and bobbin-thread cutters, and in the construction shown carries an anti-friction roll 113' which coacts with and serves to operate the bobbin-thread cutting and clamping device. The operation of said device 101 from the rod 113 is effected preferably by means of an intermediate member in the form of a cam-lever 110 connected to the device 101 and having two cam faces 110' and 110'', the former of which coacts with the manually controlled operating means, one element of which is the rod 113, and the latter of which coacts with the auto-

130

matic operating means, which will be hereinafter described. At the rear end thereof the connecting-rod 113 is pivoted to a short connecting-rod or link 114, the rear end of which is in turn pivoted to an oscillatory member, which in this case is a plate 116 pivoted at 116' on the arm of the machine near the lower end thereof. This plate is normally held in a stationary position 5 against a stop 117 by a spring 115, which latter also serves to return the said plate 116, the link 114, the connecting-rod 113 and the shears of the needle-thread cutter to their normal positions after such parts have been 10 operated. The plate 116 also carries a spring-pressed by-pass pawl 120 having a working face in the path of an actuator, such as an anti-friction roll 121 on the rod 30, by means of which actuator the plate 15 116 is oscillated and the thread-cutter actuated, and by means of which rod the presser-bar may be raised on the depression of a treadle (not shown) by the operator. At its upper end the rod 30 has a slot 122 of 20 sufficient length to provide for a certain lost motion to permit the thread-cutters and a needle-thread pull-out hereafter described to be operated before the presser-bar lever 123 is operated to raise the presser-bar. An 25 independent spring 124 is employed for returning the connecting-rod 30 to its normal position in addition to that shown at 125 for lowering the presser-bar and its lever.

The connecting-rod 30 also constitutes a 30 means for actuating a device for pulling the cut end of the needle-thread out of the work. The pull-out proper is in this case a plate 145' having a needle-opening therein and located in a horizontal plane at the lower 35 end of an angle-lever 145 pivoted on the sewing machine head at 146. This needle-thread pull-out is actuated by a long lever 147 pivoted at 148 and extending at its rear end into the path of movement of the rod 30. 40 This lever 147 is forked at 147' at its rear end to straddle an actuator, such as 150, carried by the rod 30, the forked portion of the lever having a cam-shaped face coacting with the actuator 150, and the parts being 45 so organized that the rod 30 at the proper point in its descent, after the threads have been cut, operates the lever 147 to shift the pull-out toward the rear of the machine to withdraw the needle-thread from the cloth 50 before the presser-bar is raised. The spring 151 serves to return the lever 147 and the pull-out to their normal positions. When the rod 30 is pulled down the actuator 121 will engage the working face of the pawl 120 to oscillate the plate 116 and operate the thread-cutters, and the continued downward movement of the rod 30 will cause the actuation of the pull-out and the raising of the presser-bar.

65 After the work has been shifted to a new

position, the rod 30 may be permitted to rise, and the actuator 121 will ride past the pawl 120 to a point above the same in its normal position. At the same time the various springs will return the needle-thread 70 cutters, the pull-out and the presser-bar to their normal positions. Thereupon the machine may be started again by turning the rock-shaft 46, which will cause the elbow-lever 36 to be operated and the pulley 35 to 75 be clutched to the pulley 34 again, and at the same time the slide-bar will release its stop-ring and the pull-off 87 will be shifted to its working position and take an additional length of thread from the needle-thread supply. This operation also resets the slide-latch and locks the same with its rear end in position to be operated again by the lever 74 at the proper time.

I have hereinbefore stated that the cut end 80 of the bobbin-thread will be clamped as soon as cut and held clamped until, after restarting the machine, a sufficient number of stitches has been made to lock the bobbin-thread firmly in the work, when the bobbin-thread clamp may be released automatically. In Figs. 5 to 8 inclusive, I have illustrated the successive stages in the operation 85 of cutting the two threads and restoring the needle-thread cutter and the bobbin-thread 90 cutting and clamping device to their normal positions. Fig. 5 shows the parts in their normal positions, with the machine ready to start. After making the desired number of 95 stitches the machine is automatically stopped, 100 and thereupon the cutters are operated manually, as hereinbefore described. The positions of the parts at the moment that the cutting stroke is finished are illustrated in Fig. 6, the intermediate or cam-lever 110 105 being shifted at such time by the manually-controlled actuator or antifriction roll 113' on the rod 113. Fig. 7 shows the positions of the parts on the release of the manually 110 controlled operating means, at which time 115 the needle-thread cutter is returned to its normal position and the manually-controlled actuator 113' is shifted out of operative relation with the intermediate or cam-lever 110. With the parts in this position it will 120 be noted that the manually-controlled actuator can not operate said cam-lever again until said cam-lever is returned to its original position (shown in Fig. 5). The cam-lever 110 is now in position to coact with 125 the automatic means for operating the same, and this automatic action may take place at any time after the machine has been restarted and a sufficient number of stitches made to assure the locking of the bobbin-thread in the work. Usually the cam-lever 110 will be actuated and the combined bobbin-thread cutting and clamping device released from the cut end of the bobbin-thread 125 and restored to its normal position after 130

making a series or predetermined number of stitches, as for example, a series of stitches for a single pair of holes in the button. A convenient time to release the bobbin-thread clamp is the moment when the button-holder is shifted to bring the second pair of holes in the button into position to coöperate with the needle. This movement is controlled by the lever 27, and I have shown at 160 an arm projecting from said lever and carrying an actuator or roll 160' which coacts with the cam-face 110' of the cam-lever 110 and operates said cam-lever and hence the bobbin-thread cutter and clamp automatically when the lever 27 is shifted to the position shown in Fig. 8 to shift the position of the button-holder to bring another pair of holes in the button into working relation with the needle. It will be noted that this arm 160 not only returns the bobbin-thread cutter and clamp to its normal position, as shown in Figs. 5 and 8, but that said arm itself also returns automatically to the position shown in Figs. 5, 6 and 7 when the new series of stitches is completed and the machine automatically stopped, the lever 27 shifting back to such other position on such automatic stopping of the machine. Hence the actuator 160' will also be in an inoperative position with respect to the bobbin-thread clamp, as shown in Fig. 5, at the time that the manually-controlled operating means is brought into action, the manually-controlled means and the automatic means for operating the bobbin-thread cutter and clamp thus coöperating therewith alternately.

What I claim is:

1. In a sewing machine for forming successive groups of stitches with intervening spaces, the combination with the stitch-forming mechanism, of a thread-cutter, a thread-clamp, manually-controlled means operative upon a completion of a group of stitches for operating said thread-clamp to clamp the thread, and automatic means operative during the formation of a group of stitches for operating said thread-clamp to release the thread.
2. In a sewing machine for forming successive groups of stitches with intervening spaces, of a bobbin-thread cutting and clamping device, manually-controlled means operative upon the completion of a group of stitches for operating said device to clamp the thread, and automatic means operative during the formation of a group of stitches for operating said device to release the thread.
3. In a sewing machine for forming successive groups of stitches with intervening spaces, the combination with a stitch-forming mechanism, of a combined thread cutting and clamping device, manually-controlled means operative upon the completion

of a group of stitches for operating said device, and automatic means operative during the formation of a group of stitches for operating said device to release the thread.

4. In a sewing machine for forming successive groups of stitches with intervening spaces, the combination with the stitch-forming mechanism, of a combined thread cutting and clamping device, manually controlled means operative upon the completion of a group of stitches for imparting a working movement to said device, and automatic means operative during the formation of a group of stitches for imparting a return movement to said device, for the purpose set forth.

5. In a sewing machine, the combination with stitch-forming mechanism, of a needle-thread cutter, a bobbin-thread cutter, manually-controlled means for imparting working strokes to both of said cutters and a return stroke to said needle-thread cutter, and automatic means for imparting a return stroke to said bobbin-thread cutter.

6. In a sewing machine, the combination with stitch-forming mechanism, of a needle-thread cutter, bobbin-thread cutting and clamping means, manually-controlled means for imparting working strokes to said needle-thread cutter and said bobbin-thread cutting and clamping means and a return stroke to said needle-thread cutter, and automatic means for imparting a return stroke to said bobbin-thread cutting and clamping means.

7. In a sewing machine, the combination with stitch-forming mechanism, of a needle-thread cutter, a combined bobbin-thread cutting and clamping device, manually-controlled means for imparting working strokes to said needle-thread cutter and said combined bobbin-thread cutting and clamping device and a return stroke to said needle-thread cutter, and automatic means for imparting a return stroke to said combined bobbin-thread cutting and clamping device.

8. In a sewing machine, the combination with stitch-forming mechanism, an oscillatory needle-thread cutter, an oscillatory bobbin-thread cutting and clamping device, means for imparting to said needle-thread cutter and said bobbin-thread cutting and clamping device simultaneous working movements, and means for imparting to said needle-thread cutters and said bobbin-thread cutting and clamping device successive return movements.

9. In a sewing machine, the combination with stitch-forming mechanism, and with a thread clamp, of manually-controlled means for operating said thread clamp to clamp the thread, and automatic shifting mechanism operative on the completion of a predetermined number of stitches for operating said thread clamp to release the thread.

10. In a sewing machine, the combination with stitch-forming mechanism, a thread-cutter and a thread-clamp, of manually-controlled means for operating said clamp 5 to clamp the thread, a button-holder, and automatic button-holder-shifting mechanism operative on the completion of a predetermined number of stitches for operating said clamp to release the thread.
11. In a sewing machine, the combination with stitch-forming mechanism, a thread-cutter and a bobbin-thread clamp, of manually-controlled means for operating said clamp to clamp the thread, a button-holder, 15 and automatic button-holder-shifting mechanism operative on the completion of a predetermined number of stitches for operating said clamp to release the thread.
12. In a sewing machine, the combination 20 with stitch-forming mechanism, and with a combined bobbin-thread cutting and clamping device, of manually-controlled means for imparting a working movement to said device, and automatic shifting mechanism operative on the completion of a predetermined number of stitches for imparting a return movement to said device.
13. In a sewing machine, the combination 25 with stitch-forming mechanism, and with a combined bobbin-thread cutting and clamping device, of manually-controlled means for imparting a working movement to said device, a button-holder, and automatic button-holder-shifting mechanism operative on the completion of a predetermined number of 30 stitches for imparting a return movement to said device.
14. In a sewing machine, the combination 35 with stitch-forming mechanism, of a needle-thread cutter, a bobbin-thread cutter, manually-controlled means for imparting working strokes to both of said cutters and a return stroke to said needle-thread cutter, and automatic shifting mechanism operative on the completion of a predetermined number 40 of stitches for imparting a return stroke to said bobbin-thread cutter.
15. In a sewing machine, the combination 45 with stitch-forming mechanism, of a needle-thread cutter, bobbin-thread cutting and clamping means, manually-controlled means for imparting working strokes to said needle-thread cutter and the bobbin-thread cutting and clamping means and a return 50 stroke to the needle-thread cutter, and automatic shifting mechanism operative on the completion of a predetermined number of stitches for imparting a return stroke to said bobbin-thread cutting and clamping means.
16. In a sewing machine, the combination 55 with stitch-forming mechanism, of a needle-thread cutter, bobbin-thread cutting and clamping means, manually-controlled means for imparting working strokes to said 60
- needle-thread cutter and the bobbin-thread 65 cutting and clamping means and a return stroke to the needle-thread cutter, a button-holder, and automatic button-holder-shifting mechanism operative on the completion of a predetermined number of stitches for imparting a return stroke to said bobbin-thread cutting and clamping means.
17. In a sewing machine, the combination with stitch-forming mechanism, of a combined thread cutting and clamping device 70 having a sharp cutting edge and a rounded clamping edge, manually-controlled means for operating said device, and automatic means operative on the completion of a predetermined number of stitches for imparting 75 a return movement to said device.
18. In a sewing machine, the combination with stitch-forming mechanism, of a bobbin-thread clamp mounted upon the throat-plate, clamp-actuating means, and means for pressing 80 said bobbin-thread clamp down onto the throat-plate and movably holding it in clamping position relatively thereto.
19. In a sewing machine, the combination 85 with stitch-forming mechanism, of a combined bobbin-thread cutting and clamping device mounted upon the throat-plate, means for actuating said device, and movable means for engaging with and pressing said device down onto the throat-plate. 90
20. In a sewing machine, the combination 95 with stitch-forming mechanism, of a thread-clamp mounted on the throat-plate, clamp-actuating means, and presser-bar-actuating means for pressing said thread-clamp down onto the throat-plate. 100
21. In a sewing machine, the combination 105 with stitch-forming mechanism, of a bobbin-thread clamp mounted upon and movable across the throat-plate, clamp-actuating means, and presser-bar-actuating means for pressing said bobbin-thread clamp down onto the throat-plate.
22. In a sewing machine, the combination 110 with stitch-forming mechanism, of a clamping-plate secured to the throat-plate and movable slightly relatively thereto, a bobbin-thread clamp mounted upon the throat-plate and under the clamping-plate, clamp-actuating means and means for exerting a 115 downward clamping pressure upon said clamping-plate.
23. In a sewing machine, the combination 120 with stitch-forming mechanism, of a clamping-plate secured to the throat-plate and movable slightly relatively thereto, a bobbin-thread clamp mounted upon the throat-plate and under the clamping-plate, clamp-actuating means and a presser-bar co-operative 125 with said clamping-plate for exerting a downward clamping pressure upon said clamp.
24. In a sewing machine, the combination

- with stitch-forming mechanism including a driving shaft, of a normally inoperative loop-detainer, a cam-wheel driven by said shaft and having a cam face controlling the 5 throw of said loop-detainer into action, an automatic stop mechanism organized and timed to stop the stitch-forming mechanism with the cam on the driving shaft in position for operating said loop-detainer, and a 10 manually-controlled thread-cutter operative subsequent to the action of said stop mechanism.
25. In a sewing machine, the combination with stitch-forming mechanism including a driving shaft, of a normally inoperative loop-detainer, a cam-wheel driven by said shaft and having a locking recess controlling the throw of said loop-detainer into action and also serving to lock the loop-detainer 15 in its operative position, an automatic stop mechanism organized and timed to stop the stitch-forming mechanism with the cam on the driving shaft in position for operating and locking said loop-detainer, and a 20 manually-controlled thread-cutter operative subsequent to the action of said stop mechanism.
26. In a sewing machine, the combination with stitch-forming mechanism, of an automatic stop mechanism therefor, a normally inoperative loop-detainer controlled by said 30 stop-mechanism and rendered operative thereby upon the stopping of the stitch-forming mechanism and a pair of manually controlled coacting thread-cutting shears co-operative with said loop-detainer.
27. In a sewing machine, the combination with stitch-forming mechanism, of an automatic stop mechanism therefor, a normally 40 inoperative loop-detainer and spreader controlled by said stop mechanism and rendered operative thereby upon the stopping of the stitch-forming mechanism and a pair of manually-controlled coacting thread-cutting 45 shears operative in the path of one side only of a loop engaged by said loop-detainer.
28. In a sewing machine, the combination with stitch-forming mechanism embodying a needle and a bobbin, of an automatic stop 50 mechanism therefor, a loop-spreader controlling the needle-thread and controlled by the stop mechanism and rendered operative thereby upon the stopping of the stitch-forming mechanism, a needle-thread cutter 55 operative in the path of one side only of a loop engaged by said loop-spreader, and manually-controlled thread-cutting means.
29. In a sewing machine, the combination with stitch-forming mechanism embodying a 60 needle and a bobbin, of an automatic stop mechanism, a loop spreader controlling the needle-thread and controlled by the stop mechanism, a needle-thread cutter operative in the path of one side only of a loop en-
- gaged by said loop-spreader, bobbin-thread 65 cutting and clamping means, manually controlled means for imparting a working stroke to said needle-thread cutter and the bobbin-thread cutting and clamping means and a return stroke to the needle-thread cutter, and automatic means for imparting a return stroke to said bobbin-thread cutting and clamping means.
30. In a sewing machine, the combination with stitch-forming mechanism including 70 the presser-bar, of separated cutting and clamping members one of which is movable relatively to the other, a combined thread cutting and clamping device having a sharp cutting edge and a rounded clamping edge 75 co-operative respectively with said cutting and clamping members and being operative therebetween, means for imparting working and return strokes to said device, and means including said presser-bar controlling the 80 clamping pressure of said movable member.
31. In a sewing machine, the combination with stitch-forming mechanism including the presser-bar, of two separated clamping members one of which is movable relatively 85 to the other, a thread clamp operative between said clamping members, clamp-actuating means, and means including said presser-bar controlling the clamping pressure of said movable clamping member. 90
32. In a sewing machine, the combination with stitch-forming mechanism including the presser-bar, of two separated clamping members one of which is movable relatively 95 to the other, a thread-cutter operative between said clamping members, cutter-actuating means, and means including said presser-bar controlling the clamping pressure of said movable clamping member. 100
33. In a sewing machine, the combination with stitch-forming mechanism including 105 the presser-bar, of two separated clamping members one of which is movable relatively to the other, a combined thread cutting and clamping device operative between said 110 clamping members, means for actuating said device, and means including said presser-bar controlling the clamping pressure of said movable clamping member.
34. In a sewing machine, the combination with stitch-forming mechanism including 115 the presser-bar, of two separated clamping members one of which is yieldingly movable relatively to the other, a thread clamp operative between said clamping members, 120 clamp-actuating means, and means including said presser-bar movable to and from position for exerting a clamping pressure on said movable clamping member.
35. In a sewing machine, the combination with stitch-forming mechanism including 125 the presser-bar, of two separated clamping members one of which is yieldingly movable

relatively to the other, a combined thread cutting and clamping device operative between said clamping members, means for actuating said device, and means including
5 said presser-bar movable to and from position for exerting a clamping pressure on said movable clamping member.

Signed at Philadelphia in the county of Philadelphia and State of Pennsylvania this 23d day of December A. D. 1903.

DANIEL MILLS.
